US0D1070183S

(12) **United States Design Patent** (10) **Patent No.:** **US D1,070,183 S**
(45) **Date of Patent:** **** Apr. 8, 2025**

(54) **WIG STAND**

(71) Applicant: **Sherrian Carthy**, Philadelphia, PA
(US)

(72) Inventor: **Sherrian Carthy**, Philadelphia, PA
(US)

(**) Term: **15 Years**

(21) Appl. No.: **29/892,026**

(22) Filed: **May 12, 2023**

(51) LOC (15) Cl. **28-04**

(52) U.S. Cl.

USPC **D28/93**

(58) **Field of Classification Search**
